F. T. CULLEN.
GAS SAVER AND CARBON DECOMPOSER,
APPLICATION FILED JAN. 8, 1917.

1,266,216.

Patented May 14, 1918.

UNITED STATES PATENT OFFICE.

FREDERICK T. CULLEN, OF PETALUMA, CALIFORNIA, ASSIGNOR OF ONE-HALF TO
JOHN F. CULLEN, OF PETALUMA, CALIFORNIA.

GAS-SAVER AND CARBON-DECOMPOSER.

1,266,216.

Specification of Letters Patent. Patented May 14, 1918.

Application filed January 8, 1917. Serial No. 141,069.

To all whom it may concern:

Be it known that I, FREDERICK T. CULLEN, a citizen of the United States, residing at Petaluma, in the county of Sonoma and 5 State of California, have invented new and useful Improvements in Gas-Savers and Carbon-Decomposers, of which the following is a specification.

This invention relates to an apparatus to 10 be used in combination with internal combustion engines, and particularly to an apparatus which not only reduces the quantity of fuel consumed but also prevents carbon formation when low gravity fuels are employed.

One of the objects of the present invention is to provide means for introducing a mixture of air and steam to the inlet manifold of an internal combustion engine, and 20 in conjunction therewith to provide a valve whereby the quantity of said mixture admitted may be regulated. Another object of the invention is to provide a simple, easily applied heater for generating the 25 steam.

The invention consists of the parts and the construction and combination of parts as hereinafter more fully described and claimed, having reference to the accompanying drawings, in which—

Figure 1 is a side elevation of an internal combustion engine, showing the application of the invention.

Fig. 2 is an enlarged, central, vertical 35 section of the mixer.

Referring to the drawings in detail, A indicates the cylinder head of an internal combustion engine, 2 the cylinders, 3 the exhaust manifold, and 4 the inlet manifold. 40 The type of engine employed in the present instance is water-jacketed, as shown at 5, and the cooling water employed is circulated in the usual manner through a radiator 6. Extending through the exhaust manifold is a pipe 7 which serves the function of a steam generator, and connected with one end of said pipe, by means of a union 8, is a goose neck 9 and connecting said goose neck with the jacket of one of the cylinders 45 is a pipe 10 which is provided with a regulating valve 11.

Suitably supported on one side of the engine is a casing 12, interiorly of which is formed a combination trap and mixing 55 chamber 13 which is connected with the

opposite end of pipe 7 by means of a pipe 14. This pipe is inclosed by a second pipe 15 which forms a jacket about same and which also permits a certain amount of the 60 exhaust gases to escape at the open end indicated at 16. The opposite end of pipe 15 connects directly with the exhaust manifold and thereby forms a communication which permits a part of the exhaust gases 65 to escape around the pipe 14 and out through the open end 16; this jacket being merely provided for the purpose of retaining the pipe 14 as hot as possible to prevent re-condensing of the steam generated in the 70 pipe 7.

Connected with the lower end of the casing 12 and communicating with chamber 13 is an S-shaped trap pipe 17, the function of which will hereinafter be described, and 75 connecting the chamber 13 with the inlet manifold is a pipe 18 upon which is mounted a valve 19 which may be opened or closed from the dashboard by means of a rod 20 and a handle extension 21.

In actual operation, with the valve 11 slightly open, a certain amount of water is permitted to enter the pipe 7. This is constantly maintained at a high temperature while the engine is running and therefore 80 constantly causes the water to turn into steam before it escapes through pipe 14 into the trap and mixing chamber 13. Any water which may have condensed or passed through the pipe 7 is here caught by an inclined 85 screen 22 which causes it to drain down to one side and collect in the bottom of the chamber 13, as shown in Fig. 2. The steam admitted is permitted to escape through the connected pipe 18 and will thus enter the 90 manifold through the valve 19, the quantity admitted being controlled entirely by the opening of said valve. The amount of water collected or trapped in chamber 13 will never assume a higher level than the highest 95 point in the trap pipe 17. It is, therefore, permitted to freely discharge through same the moment said level is obtained.

The comparatively high suction maintained in the inlet manifold while the engine is running causes a suction or vacuum to be maintained in the chamber 13 and also in the pipes 14, 7 and 10. The water from the jacket 5 is in this manner raised by suction to the steam generator and is also 105 constantly withdrawn from same in the form

of steam. Air is also admitted through the trap pipe 17 and as it passes through the water collected in the lower end of the chamber, it can readily be seen that this 5 will gradually disappear after the engine is started as the air will gradually absorb the water. The connecting end of pipe 18 being turned up, as at 23, prevents the water from entering in any quantity and permits 10 the moist air to thoroughly mix with the steam before it passes through the pipe 18 into the inlet manifold. The valve 19 may be closed at any time as the rod 20 is within 15 convenient reach of the driver. The flow of auxiliary air and steam may, therefore, be cut out at any time desired or the amount admitted may be regulated to suit varying 20 conditions and speeds.

In actual practice, it has been found that 20 the admission of air and steam as a mixture not only reduces the quantity of fuel consumed but also serves as a means for decomposing or preventing carbon formations within the cylinders, particularly when low 25 gravity fuel oils, such as distillate or kerosene, are employed. It has also been found that it increases the mileage and general power output of the engine and maintains the sparking plugs so clean that ignition 30 troubles are practically eliminated.

The goose neck 9 employed is higher in elevation than the water level within the radiator and prevents water from running through the generator and filling the trap 35 18 when the engine is not running, due to the fact that the steam generated in the pipe 7, immediately after stopping of the engine, creates sufficient pressure to overcome 40 tendency to siphon and forces the water in gooseneck 9 back over the highest point of the latter; in other words, it does not become necessary to open or close the valve 11 once it has been regulated and set as no 45 water can pass through the steam generator 7 except when the suction produced in the inlet manifold, when the engine is running, draws the water through the goose neck, as 50 previously described. The whole attachment is automatic in operation and will require no attention on the part of the operator when once installed. The pipe 18 employed is preferably constructed of rubber to reduce vibration as much as possible; and I wish it understood that the materials 55 and finish of the other parts of the attachment may be such as the experience and judgment of the manufacturer may dictate.

I also wish it understood that various changes in form, proportions and minor details of construction may be resorted to 60

within the scope of the appended claims and that I do not wish to limit myself to the specific design and construction here shown.

Having thus described my invention, what I claim and desire to secure by Letters Patent is—

1. In a device of the type set forth, a pipe connected at one end to the engine water jacket and having a part extending through the exhaust manifold and therewithout, a 70 jacket connected at one end to the exhaust manifold and surrounding the part of the pipe without the manifold, the other end of the pipe jacket being open to allow the exhaust gases from the manifold to escape 75 therefrom, and means between said other end of the pipe and inlet manifold of the engine for conveying steam to said engine inlet manifold.

2. In a device of the type set forth, a pipe 80 having one end connected to the engine water jacket and having an intermediate part extending through the exhaust manifold and its other end extending without the exhaust manifold, said first named end of the pipe 85 being formed with a gooseneck between the engine water jacket and exhaust manifold, a jacket inclosing said last named pipe end, and means to conduct steam from the pipe to the engine inlet manifold. 90

3. In a device of the type set forth, a pipe connected at one end to the engine water jacket and having a part extending through the exhaust manifold and having its other end portion extending outside of 95 said manifold, a jacket connected at one end to said manifold and surrounding said other part end of the pipe which extends without the manifold in spaced relation thereto, and means to conduct steam from said other 100 end of the pipe to the engine inlet manifold.

4. In a device of the type set forth, a pipe connected at one end to the engine water jacket and having a part extending through 105 the exhaust manifold and having its other end portion extending outside of said manifold, means to conduct heated gases from the manifold to said other end of the pipe to heat the latter, and means to conduct steam 110 from said other end of the pipe to the engine inlet manifold.

In testimony whereof I have hereunto set my hand in the presence of two subscribing witnesses.

FREDERICK T. CULLEN.
